UNITED STATES PATENT OFFICE.

MOSES AMOS, OF ATLANTA, GEORGIA.

HOLDER FOR BOX-COVERS.

1,331,972.

Specification of Letters Patent. Patented Feb. 24, 1920.

Application filed April 11, 1919. Serial No. 289,455.

To all whom it may concern:

Be it known that I, MOSES AMOS, a citizen of the United States, residing at Atlanta, in the county of Fulton, State of Georgia, have invented a new and useful Holder for Box-Covers; and I do hereby declare the following to be a full, clear, and exact description of the invention, such as will enable others skilled in the art to which it appertains to make and use the same.

The invention relates to holders for box covers and has for its object to provide a holder for covers wherein the covers will be held when labels are being pasted on the same. It is the present practice in drug stores and the like to paste labels on pill boxes by hand or a labeling machine. However the difficulty in these methods is that the labels are not securely applied thereto, for the reason that the covers, that may be round, square or oblong are not reinforced against a solid surface during the pasting operation, therefore it is another object to provide a holder wherein it will be possible to hold pill boxes of different shapes that are commonly in use during the pasting operation.

With the above and other objects in view the invention resides in the combination and arrangements of parts as hereinafter set forth, shown in the drawings, described and claimed, it being understood that changes in the precise embodiment of the invention may be made within the scope of what is claimed without departing from the spirit of the invention.

Referring to the drawings:—

Figure 1 is a perspective view of the holder, showing an oblong box cover applied thereto and ready to have a label applied thereto.

Fig. 2 is a top plan view of the holder.

Fig. 3 is a longitudinal sectional view through the holder taken on line 3—3 of Fig. 2.

Referring to the drawings the numeral 1 designates the base, which may be of any suitable size or shape. Secured to one end thereof by means of a screw 2 is a block 3 and pivoted to a screw 4 which enters the upper surface of the block 3 is a horizontally pivoted member 5, the end 6 of which is adapted to rest on a square block 7 at the other end of the base 1, said block 7 being

secured to the base by means of the screw 55 8. A round block 9 is secured by means of a screw 10 to the horizontally pivoted member 5.

When it is desired to paste a label on a box cover of an oblong shape, such for instance as that shown and designated by the numeral 11 in Fig. 1, the free end of the member 5 is swung off of the block 7 the cover 11 telescopically placed thereon, then the member 6 is positioned so that the free 65 end thereof will be on the block 7. The cover 11 when on the member 6 will be against a hard smooth surface when the label is being applied thereto, therefore the adhesion of the same will be even and uniform over its entire surface.

If it is desired to place a label on a round cover, the cover is placed on the block 9 and then the round label is applied thereto, and when labels are being applied to square 75 boxes the covers are placed on the square block 7, that is after the pivoted member 5 has been moved so that its end 6 is out of engagement with the block 7.

The block 9 forms a handle member, 80 whereby the pivoted arm 5 may be swung laterally to and from the block 7, as well as forming means for holding a round box cover when a label is being applied to the same.

From the above it will be seen that a pill box cover holder has been provided that will be cheap in construction and one wherein various shapes of covers, may be held in such a manner that the labels may be placed thereon, so that the adhesion thereof, will be uniform and the cover present a smooth appearance to the eye.

The invention having been set forth, what is claimed as new and useful is:—

1. A device for supporting a portion of a box for affixing labels thereon comprising a base, a spacing member secured to said base, and having a horizontally pivoted arm or member carried thereby, said arm or member having a free end disposed in relative position for engaging a suitable block or support, and means carried by said arm or member for engaging and supporting a portion of said box and adapted to prevent 100 the longitudinal and transverse movement of the same.
2. A holder for box covers comprising a

base, a spacing block secured to one end of said base, a horizontally pivoted cover receiving arm pivoted to the spacing block, a square block at the other end of the base, 5 said square block being adapted to receive a square box cover and a round block carried by the pivoted arm for the reception of a round box cover and also forming handle means for horizontally swinging the arm 10 so that the free end thereof may be placed

into and out of engagement with the upper surface of the square block at the other end of the base.

In testimony whereof I have signed my name to this specification in the presence of 15 two subscribing witnesses.

MOSES AMOS.
